UNITED STATES PATENT OFFICE.

REGINALD LESLIE GOODING, OF BRIDGETOWN, BRITISH WEST INDIES.

SCARF-RETAINER.

SPECIFICATION forming part of Letters Patent No. 739,668, dated September 22, 1903.

Application filed May 9, 1903. Serial No. 156,466. (No model.)

To all whom it may concern:

Be it known that I, REGINALD LESLIE GOODING, a subject of the King of Great Britain, and a resident of Bridgetown, Island of Barbadoes, British West Indies, have invented a new and Improved Scarf-Retainer, of which the following is a full, clear, and exact description.

The invention relates to wearing-apparel; 10 and its object is to provide a new and improved scarf retainer or clip which is simple and durable in construction, easily applied, and arranged to securely hold the depending portions of the scarf or other tie securely in 15 place on the shirt-bosom.

The invention consists of novel features and parts and combinations of the same, as will be more fully described hereinafter and then pointed out in the claim.

20 A practical embodiment of the invention is represented in the accompanying drawings, forming a part of this specification, in which similar characters of reference indicate corresponding parts in all the views.

25 Figure 1 is a reduced front elevation of the improvement as applied. Fig. 2 is a front elevation of the same. Fig. 3 is an enlarged sectional plan view of the same on the line 3 3 of Fig. 2, and Fig. 4 is a perspective view 30 of the improvement.

The improved scarf or tie retainer is made from a single piece of spring-wire bent to form a bottom piece A of U shape and having its side members A' extending approximately parallel one to the other to terminate at their ends in inwardly and upwardly curved cross-arms A², from which extend clamping-arms A³, arranged one alongside the other and curved downward and upward approximately midway between the side members A', the clamping-arms A³ terminating in a ball A⁵ or similar ornament a distance from the middle portion of the U-shaped bottom piece A.

40 The extreme forward ends of the clamping members A³ are preferably soldered together, and the dip of the clamping members is near the terminal end and normally slightly above

the plane extending through the side members A' of the bottom piece.

Now by the arrangement described the middle portion A⁴ of the bottom piece A can be readily passed under the overlying flap B of a shirt-bosom to guide the clip, so as to finally engage the ball end of the clamping members A³ with the top of the depending flaps or aprons C of the scarf or tie to allow the clamping members A³ to yield upwardly, and thereby clamp the depending aprons C firmly in place on the outer face of the bosom-flap B. 55

The cross-arm A² limits the inward sliding movement of the retainer or clip by abutting against the outer edge of the flap B.

Now from the foregoing it will be seen that the device is very simple in construction and 65 can be rendered highly ornamental by the use of precious stones or the like on the ball A⁵, and the retainer firmly secures the scarf-aprons in position on the bosom to give a dressy appearance to the user.

Having thus described my invention, I claim as new and desire to secure by Letters Patent—

As a new article of manufacture, a tie-retainer made of a single piece of wire, formed 75 into a U-shaped bottom piece having its side members terminating at their ends in inwardly and upwardly turned cross-arms, from which extend integral clamping members, curved first downwardly and then upwardly, 80 and extending approximately parallel midway between the side members of the bottom piece to within a short distance of the middle or connecting portion of the said bottom piece and having their ends secured together, 85 and an ornamental ball secured to the united terminals of the said clamping members, as set forth.

In testimony whereof I have signed my name to this specification in the presence of 90 two subscribing witnesses.

REGINALD LESLIE GOODING.
